INVENTOR

Frank L. Dyer

UNITED STATES PATENT OFFICE.

FRANK L. DYER, OF MONTCLAIR, NEW JERSEY.

MEASURING DEVICE FOR COLLAPSIBLE TUBES.

Application filed September 28, 1921. Serial No. 503,718.

To all whom it may concern:

Be it known that I, FRANK L. DYER, a citizen of the United States, residing at Montclair, in the county of Essex and State of New Jersey, have invented a certain new and useful Measuring Device for Collapsible Tubes, of which the following is a full, clear, and exact specification.

My invention relates to an improved measuring device for collapsible tubes, of the type disclosed in my application for patent filed January 8, 1921, Serial No. 435,972, wherein a tubular body communicates with the interior of the tube and is provided with a discharge opening and with a plunger movable with respect to the same, whereby when the tube is squeezed the paste-like material forced into the tubular body will move the plunger longitudinally, while by reversing the movement of the plunger a measured quantity of the material will be ejected through the discharge opening, suitable means being provided for uncovering and closing said opening to permit the operations described to take place.

The objects of the present invention are to simplify the construction of the device, to improve its operation, and to make more easy the assembling of the parts in manufacture. A further object, in its preferred form, is to provide a device in which the discharge opening will be automatically closed when the desired amount of material is ejected, thereby overcoming the necessity of doing this manually and assuring the normal closure of the discharge opening to prevent the material from drying or caking within the same.

The device may be in the form of a separate attachment to be removably secured to the neck of a collapsible tube, as described in my said application, or it may be manufactured as a part of such tube. By reason of its great cheapness and ease of assembling, the extra cost of manufacturing tubes equipped with my improved device is slight, since I do away entirely with the present screw cap and the necessary threading operations on the neck and cap.

In order that the invention may be better understood, attention is directed to the accompanying drawing forming part of this specification, and in which:

Fig. 1 is a longitudinal section through the upper or neck-end of a collapsible tube with the present improvements thereon,

showing in dotted lines the upper position of the plunger with the discharge opening uncovered.

Fig. 2, a section on the line 2—2 of Fig. 1, 60 the discharge opening in the neck being indicated in dotted lines.

Fig. 3, a sectional view similar to Fig. 2, showing a separate stop pin, and illustrating the sleeve-like plunger turned to close the 65 discharge opening; and

Fig. 4, a detail view showing the discharge opening, slot and stop as in Fig. 1, but illustrating the inclining of the upper edge of the slot to automatically close the 70 discharge opening.

In the above views, corresponding parts are represented by the same numerals.

The collapsible tube 1, is of usual construction, the paste-like material being introduced within its open lower end which is then closed and sealed. The neck 2 constitutes the tubular body of the measuring device, and is formed as a part of the tube. This neck is longer than usual and is preferably larger in diameter, these dimensions depending upon the amount of material to be discharged for each use. It is provided with a discharge opening 3, of desired size and form.

Fitted within the tubular body 2 is a plunger 4 in the form of a sleeve with a closed upper end and an open lower end, the upper end being beaded at 5 and extending slightly beyond the tubular body so as to permit the 90 plunger 4 to be given a turning movement within the tubular body. To facilitate this, the bead 5 is preferably knurled as shown.

The sleeve or plunger 4 is formed with a slot 6 which may uncover the opening 3 during the reverse or discharge stroke of the plunger, while by slightly rotating the plunger the slot 6 will be moved out of line with the opening and the latter will be closed as during the upward stroke of the plunger and 100 when the tube is not in use.

To limit the partial rotary movement of the plunger I provide a stop 7 in the bore of the tubular body, which stop is engaged by one or the other longitudinal edge of the 105 slot 6, according as the plunger is in position to open (Fig. 2) or close (Fig. 3) the discharge opening 3. This stop also limits the upward or outward movement of the plunger, when the lower edge of the slot 6 engages the same, as shown in dotted lines in 110 Fig. 1. It may also limit the downward or

inward movement of the plunger by engagement with the upper edge of the slot, or this movement may be limited by engagement between the bead 5 and the edge of the 5 tubular body.

The sleeve or plunger 4 is formed preferably of very thin sheet brass or copper, or other resilient and ductile metal, by drawing or stamping, the slot 6 being cut therein 10 by a suitable die. By using thin resilient metal, it will make a tight fit with the tubular body, the slot 6 permitting the sleeve or plunger to slightly expand into close contact with the bore of the tubular body under the 15 effect of the pressure of the paste-like material. At the same time, the use of resilient metal permits the plunger to be assembled after the stop 7 is formed in the tubular body, since by pressing the plunger inwards 20 the lower edge of the slot 6 will ride over the stop 7 and snap beneath the same.

The stop 7 may be a separate small pin passing through the wall of the tubular body, as in Fig. 3, but it is formed preferably as in Fig. 2, by depressing the metal of the tubular body by a sharp tool, thus forming the stop as a projection or protuberance in the metal.

In the preferred form (Fig. 4) I make 30 the slot 6 with an inclined upper edge 8 which engages the stop 7 near the end of the inner stroke of the plunger, and automatically turns the same to close the discharge opening, as will be understood. This arrangement is especially desirable with large-sized tubes; for small-sized tubes it may not be desirable on account of the limited size of the parts.

If desired, the upper edge of the slot 6 40 may be formed with a small notch 9 (see Fig. 4), which receives the stop 7 when the plunger is forced all the way inwards and prevents the accidental turning of the plunger to uncover the opening 3 when the tube 45 is out of use.

Obviously the portion of the plunger above the slot 6 is a dead-end; any material entering the plunger above the slot is not ejected. This portion of the plunger may 50 be allowed to fill with the paste-like material which may harden or cake therein, or, if desired, the plunger, before assembling, may be filled above the slot with a suitable material such as soap or a plastic composition, 55 thus preventing the accumulation and caking of the paste-like material within the plunger.

In operation, the plunger 4 will be in the 60 inner position shown in full lines Fig. 1, but will be rotated to carry the slot 6 out of line with the opening 3, as in Fig. 3. The discharge opening 3 will thereby be closed and will stay closed so long as the plunger 65 4 is moved outwards without being rotated to uncover the discharge opening. The tube

1 is now squeezed and the paste-like material is forced into the plunger 4 which is thus moved outwards until arrested by the slot 7 engaging the inner or bottom edge of the slot 6. The plunger is now partially rotated, 70 as in Fig. 2, to bring the slot in line with the opening 3, and is then forced inwards, causing the paste-like material to be ejected through the opening 3. When the plunger 4 reaches its innermost position, as in full 75 lines in Fig. 1, it is then turned to carry the slot 6 out of line with, and again close, the opening, when the operation as described may be repeated. With the modification shown in Fig. 4, this final turning of the 80 plunger to close the discharge opening will be performed automatically; near the end of its inward movement, the inclined edge 8 of the slot will engage the slot pin 7, so that the further inward movement of the 85 plunger will cause the same to be rotated automatically, the notch 9 engaging the slot- 90 pin 7, when the plunger is all the way in and preventing the same from being turned accidentally to uncover the discharge opening and also keeping the discharge opening closed to prevent the material from drying and caking.

Having now described my invention, what I claim as new therein and desire to secure by Letters Patent is:

1. A collapsible tube formed with an integral tubular body having a discharge opening therein, means for uncovering and closing said opening including a plunger 100 movable slidably and rotatably with respect to said tubular body, whereby material forced from the tube by collapsing the latter will move the plunger outwards and a reverse movement of the plunger will eject a 105 measured quantity of material through said opening, substantially as set forth.

2. A measuring device for collapsible tubes, comprising a tubular body into which is forced material from the tube, a discharge opening in the wall of the tubular body, and a sleeve-like plunger rotatably and slidably mounted in the tubular body and formed with a slot adapted to be brought into and out of line with said opening, substantially 115 as set forth.

3. A measuring device for collapsible tubes, comprising a tubular body into which is forced material from the tube, a discharge opening in the wall of the tubular body, a 120 sleeve-like plunger rotatably and slidably mounted in the tubular body and formed with a slot adapted to be brought into and out of line with said opening, and a stop with which the side edges of the slot engage 125 to limit the rotatable movement of the plunger, substantially as set forth.

4. A measuring device for collapsible tubes, comprising a tubular body into which is forced material from the tube, a discharge 130

- opening in the wall of the tubular body, a sleeve-like plunger rotatably and slidably mounted in the tubular body and formed with a slot adapted to be brought into and out of line with said opening, and a stop with which the side edges of the slot engage to limit the rotatable movement of the plunger and with which the lower edge of the slot engages to limit the outward slidable movement of the plunger, substantially as set forth.
5. A measuring device for collapsible tubes, comprising a tubular body into which is forced material from the tube, and a sleeve-like plunger rotatably and slidably mounted with respect to the tubular body, one of said elements being formed with a discharge opening and the other with a slot adapted to be brought into and out of line with said opening when the plunger is moved rotatably, substantially as set forth.
6. The combination with a tubular body into which paste-like material is forced from a collapsible tube and formed with a discharge opening in its wall, a resilient sleeve-like plunger in said body having a rotatable movement therein, and formed with a cut-out portion close to its edge and adapted to be brought into and out of line with the discharge opening, and a stop on the bore of the tubular body, over which the lower edge of the cut-out portion is forced with a snap action to bring the stop within the cut-out portion and limit the rotatable movement of the plunger, substantially as set forth.
7. A measuring device for collapsible tubes, comprising a tubular body into which is forced material from the tube, a sleeve-like plunger rotatably and slidably mounted with respect to the tubular body, one of
- said elements being formed with a discharge opening and the other with a slot adapted to be brought into and out of line with said opening when the plunger is moved rotatably, and means for giving to said plunger a rotatable movement when it is moved slidably, substantially as set forth. 45
8. A measuring device for collapsible tubes, comprising a tubular body into which is forced material from the tube, a discharge opening in the wall of the tube, a projection from the bore of the tubular body, and a sleeve-like plunger rotatably and slidably mounted in the tubular body and formed with a slot adapted to be brought into and out of line with said opening and with an inclined edge which cooperates with said projection to rotatably move the plunger when it is moved slidably, substantially as 50 set forth. 55
9. The combination with a tubular body into which paste-like material is forced from a collapsible tube and formed with a discharge opening in its wall, a sleeve-like plunger in said body having a rotatable movement therein and formed with a cut-out portion adapted to be brought into and out of line with the discharge opening, said cut-out portion being formed with a notch in 65 its upper edge, and a stop on the bore of the tubular body and engaging within the cut-out portion to limit the rotatable movement of the sleeve and engaging said notch to lock the plunger against rotatable movement, 70 substantially as set forth. 75

This specification signed and witnessed this 23rd day of September, 1921.
